UNITED STATES PATENT OFFICE

2,312,665

SCREENING APPARATUS

Edward B. Moore, Chicago, Ill.

Application September 30, 1940, Serial No. 358,983

8 Claims. (Cl. 209—90)

My invention relates to screening apparatus, more particularly to apparatus for separating from a continuously progressed mass of particulate material particles of undesirable sizes and shapes, and my invention has for an object the provision of efficient and reliable apparatus of this character.

Although apparatus embodying my invention is not limited thereto, it is particularly useful in separating particles of slate or other undesirable substances from a mass of coal. It is common practice, in preparing various types of coal for marketing, to screen the material to size so as to provide substantially uniform grades of coal, each grade representing particles of such size as to pass through a selected screen having openings of the desired maximum size and to be retained on a second screen having openings of the desired minimum size. Although such screening operations are relatively efficient in grading the coal, it is well known that undersized particles of coal may remain in each grade due to the fact that it is uneconomical to carry the screening operation beyond a certain point, and it is likewise well known that the various grades of coal, particularly when mined in certain localities, will also contain a large number of pieces of relatively noncombustible material such as slate or the like. These pieces of slate are usually relatively flat as compared to the substantially cubical fracture of the coal.

The presence of these so-called "flats" in the mass of coal is highly objectionable to the purchaser, and attempts have heretofore been made to provide economical methods of removing such flats. So far as I am aware, however, all such attempts have been relatively unsuccessful and something is yet to be desired in apparatus of this character. Accordingly, it is a further object of my invention to provide an apparatus for automatically removing from a continuously moving mass of screened-to-size coal the undersized particles of coal and the objectionable flats contained therein.

In carrying out my invention in one form, I provide a screening apparatus to which the material to be screened may be continuously delivered and from which the material, after screening, is continuously discharged, which apparatus comprises an inclined screening element having a plurality of transversely extending shelves with slots of predetermined size extending along the rear edges of the shelves. In the preferred embodiment of my invention these slots constitute the spaces between adjacent

shelves, the shelves being arranged in step-like relation. The material to be screened is supplied to the upper portion of the screening element and means are provided for imparting thereto a recurrent motion which causes the material to pass from shelf to shelf downwardly of the screening element. The recurrent motion imparted to the screening element includes a horizontal reciprocating component characterized by such abrupt changes in the speed of movement that the particles, which momentarily come to rest on the shelves and which are characterized by a dimension smaller than the width or height of the slots, will be discharged through the slots, the movement being caused by the inertia of the particles. Thus flats, which momentarily rest on the shelves in flatwise relation, are separated from the mass of coal and those flats which do not occupy such a position on the shelves pass downwardly to the next shelf where they again have an opportunity of assuming the desired flatwise position for discharge through the slots.

For a more complete understanding of my invention reference should now be had to the drawing, in which:

Fig. 1 is a top plan view of an apparatus embodying my invention;

Fig. 2 is an elevational view partly in section of the apparatus shown in Fig. 1; and

Fig. 3 is an enlarged fragmentary sectional view showing a portion of the screening element and illustrating the manner in which the flats are caused to pass through the slots so as to separate the flats from the moving mass of coal.

Referring now to the drawing, I have shown my invention as embodied in a screening apparatus comprising a base 10 which is provided adjacent one end with a vertically extending frame comprising a pair of vertical supports 11 connected together at their upper ends by a cross beam 12. Suitable diagonal braces 13 may be provided for the upright members 11 if desired.

In the preferred embodiment of my invention shown, the screening element, which is movably supported on the base 10, comprises a frame which includes a pair of side members 14 rigidly connected together at their opposite ends by cross members 15 and 16 respectively. Extending transversely of the frame formed by the members 14, 15, and 16, I provide a plurality of substantially flat shelves or strips 17 which are supported at their opposite ends in the side members 14. As shown, these shelves or strips

17 are spaced vertically to provide slots 18 there-between, each shelf being spaced forwardly of the one immediately above to provide a step-like structure.

The lower end of the screening element rests, as shown best in Fig. 2, on the end member of the base 10 which is cut away to provide a track 19 for receiving the lower ends of the side members 14 and the member 15. The lower end of the screen thus rests in the track 19 and a suitable skirt or lip 20 is secured to the upper surface of the member 15 and the inner sides of the members 14 to guide or conduct the material from the screening element to a suitable conveyor (not shown) or other receiving means. As shown best in Fig. 2, the upper end of the screening element or frame is supported at each side on an adjustable hanger 21, the lower end of each of the hangers 21 being pivotally connected to a bracket 22 on the portion 16 of the screening element and the upper end of each hanger being pivotally connected to a bracket 24 secured to the cross bar 12 of the upstanding supporting frame. The screening element is thus supported in an inclined position but is free to move in a substantially horizontal direction relative to the base 10.

While any suitable mechanism may be provided for imparting to the screening element a recurrent motion of the character to be hereinafter described, I have shown for purposes of illustration a mechanism which comprises a pair of springs 25 disposed on opposite sides of the screening element and having their respective opposite ends connected to the base 10 and to the members 14 of the screening element. The operating mechanism also includes an operating bar 26 which, as shown, is pivotally connected at one end to the cross member 15 and is provided at its opposite end with a lug or cam follower 27 and adapted to be engaged by a rotatable cam 28 carried on a shaft 29, the shaft 29 being rotatably journaled in brackets 30 which extend rearwardly from the upright supporting members 11. In order to maintain the operating bar 26 and the follower 27 in contact with the surface of the cam 28 at all times, suitable biasing means may be provided for the bar 26, and for purposes of illustration I have shown a coil spring 40 associated with the pivotal connection between the bar 26 and the cam member 15 for urging the bar 26 downwardly toward the cam. The shaft 29 is adapted to be driven by any suitable power means (not shown) in a counterclockwise direction, as indicated by the arrow in Fig. 2, and the cam 28 is shaped to provide a gradually increasing radius terminating in an abrupt shoulder 31.

In the operation of the apparatus thus far described, coal or other suitable particulate material to be screened may be continuously fed to the upper end of the screening element in any desired manner, and for purposes of illustration I have shown a hopper 32 supported on the upright frame formed by the members 11 and 12. The coal issuing from the lower end of a hopper 32 engages the flat end piece 16 of the screening element and moves downwardly onto the uppermost ones of the step-like shelves 17. If it is assumed now that the shaft 29 is being rotated in the direction indicated, it will be apparent that the cam 28 will act on the cam follower 27 to move the operating rod 26 in a left-hand direction, whereupon the screening element moves in a corresponding direction, the upper end

5 swinging on the hangers 21 and the lower end sliding along the base 10. The sliding movement of the lower end is of course guided by the track 19 in which the screening element rests.

10 In Fig. 3 I have shown the relationship which the particles of coal and the flats may assume with respect to the shelf members 17 as the mass of coal passes down the inclined screening element. As there shown, certain of the flats 33 will assume a flatwise position on the shelves 17, although others of the flats, for example the one indicated by the reference numeral 34, may be carried along with the particles of coal. As soon as the cam 28 is rotated to a position wherein the cam follower 27 passes over the abrupt shoulder 31, the springs 25, having been extended during the movement of the screening element in a left-hand direction, will abruptly move the screening element at a high speed in a right-hand direction. The abrupt initiation of this high speed movement will cause the flats 33 (Fig. 3), by reason of their inertia, to be discharged through the slots 18 at the rear edges of the shelves 17. The track 19 in which the lower end 15 of the screening element is guided is provided at each side with inwardly extending portions 35 which are positioned to be engaged by the ends of the side members 14 and constitute stops for the screening element which abruptly terminate the high speed movement of the screening element under the force exerted by the springs 25. This abrupt termination of the high speed movement causes the particles of coal 36 (Fig. 3) and those flats which have not been discharged through the slots 18, for example the flat 34, to move downwardly over the shelves and it will be apparent that at each such movement the flats remaining in the mass of coal will be given an additional opportunity to assume a flatwise position on one of the shelves 17, so that by the time the mass of coal reaches the lower end of the screening element substantially all of the flats will have been removed. In addition to the flats, it will of course be apparent that any particles of coal having a dimension smaller than the height of the slots 18 will likewise be separated from the mass of coal, so that a more uniformly graded product is discharged over the skirt or lip 20 at the lower end of the screening element. Any suitable means may be provided for conveying the coal away from the lower end of the screening element upon discharge from the skirt 20; for example a belt conveyor may be provided if desired.

15 While the particular operating mechanism illustrated in the drawing is adapted to provide a recurrent motion characterized by an abruptly initiated and abruptly terminated high speed movement, the abrupt initiation causing movement of the flats through the slots and the abrupt termination causing progressive movement of the mass of coal down the inclined screen, it will be apparent that various other sequences of movement may be employed so long as the movement of the screen is a recurrent movement characterized by sufficiently abrupt speed changes to effect the desired movement of the particles with respect to the shelves 17.

20 Although the shelves 17 may be of various widths and, if desired, may be arranged in exactly horizontal relation, I have found that excellent results are obtained if the width of the shelves is only slightly greater than the top size of the graded coal to be treated. Furthermore, 25 I have found that movement of the flats through

the spaces or slots between the shelves 17 will be facilitated by arranging the shelves 17 with a slight rearward inclination from the horizontal, and in Fig. 3 I have shown the shelves as inclined from the horizontal by a small angle α . If desired, the shelves 17 may be so supported at their opposite ends on the side members 14 as to provide for angular adjustment of the shelves to vary the angle α if it is desired to change the rearward inclination of the shelves. Such adjustment of the shelves 17 will of course alter the size of the slots 18, and in some cases it may be desirable to change the inclination of the shelves without changing the size of the slots. This may be accomplished by adjusting the hangers 21, each of which is provided as shown with a turnbuckle 23 which may be rotated to lengthen or shorten the hangers 21 as desired. It may also be desirable, upon adjustment of the hangers 21, to raise or lower correspondingly the hopper 32 and any suitable means (not shown) may be provided for this purpose.

It will thus be seen that I have provided an apparatus which is of exceedingly simple construction, involving only a few parts, and which is effective in its operation to remove substantially all of the flats from a continuously progressed body of coal during passage of the coal over a screening element having a predetermined recurrent motion.

While I have shown particular embodiments of my invention, it will be understood, of course, that I do not wish to be limited thereto since many modifications may be made, and I, therefore, contemplate by the appended claims to cover any such modifications as fall within the true spirit and scope of my invention.

Having thus described my invention, what I claim and desire to secure by Letters Patent is:

1. In a screening apparatus, the combination of a screening element across which the material to be screened passes during the screening operation, said screening element including a plurality of shelf members each of which is spaced forwardly and downwardly from the preceding shelf member to provide a series of steps having discharge spaces along the rear edges thereof, and means for imparting to said screening element a recurrent motion including a horizontal reciprocating component characterized by the abrupt initiation of a high speed forward movement to cause portions of said material to be discharged rearwardly from said shelf members through said discharge spaces along the rear edges thereof and by an abrupt termination of said high speed forward movement to cause other portions of said material to be discharged from the front edge of each shelf member so as to be advanced down said steps.

2. In a screening apparatus, the combination of an inclined screening element over which the material to be screened passes during the screening operation, said screening element including a plurality of vertically spaced shelf members each of which is of a width substantially equal to the maximum graded size of the material to be screened and is positioned forwardly of the one above to provide a series of steps having discharge slots therebetween of a height less than the minimum graded size of said material, means for supplying a mass of the material to be screened to the upper portion of said screening element, and means for producing a recurrent motion of said screening element, said motion producing means including means for

abruptly initiating a high speed forward movement whereby pieces of said material on said shelf members having at least one dimension smaller than the width of said discharge slots are discharged through said slots, and means for abruptly terminating said high speed movement whereby the remaining material on said shelf members is discharged from the forward edge of each shelf progressively to move said material down said series of steps.

3. In a screening apparatus, the combination of an inclined screening element having a plurality of substantially flat shelves on which the material to be screened may momentarily rest during passage over said screening element, said screening element having slots of fixed predetermined width adjacent the rear edge of each shelf through which material of predetermined sizes and shapes may be discharged from said shelves, the discharge of material from the front edge of each shelf causing progressive movement of said material across said screening element from shelf to shelf, and means for imparting to said screening element a recurrent motion including a horizontal component characterized by abruptly initiated high speed forward movements to cause rearward discharge of some of said material through said slots and by abrupt termination of said high speed forward movements to discharge some of said material from the forward edges of said shelves whereby said material advances forwardly down said screening element and is discharged forwardly therefrom.

4. In a screening apparatus, the combination of an inclined frame, a plurality of substantially flat shelves extending transversely of said frame, each shelf being of a width substantially equal to the maximum graded size of the material to be screened, said shelves being inclined rearwardly at a small angle from the horizontal and spaced to provide unobstructed openings of predetermined width between said shelves, means for causing a mass of particulate material to pass progressively down said inclined frame from shelf to shelf whereby discrete particles of said mass momentarily rest on said shelves, and means for abruptly moving said frame to cause some of the particles on said shelves to pass through the spaces between said shelves.

5. In a screening apparatus, a screening element comprising an inclined frame having a plurality of flat shelves of a width substantially equal to the maximum graded size of the material to be screened extending transversely thereof and having unobstructed slots of fixed predetermined height extending along the rear edge of each shelf, means for causing a mass of particulate material to pass progressively downwardly over said screening element from shelf to shelf whereby discrete particles of said mass come to rest momentarily on said shelves, and means for abruptly moving said frame forwardly at recurrent intervals whereby the inertia of said particles causes certain of said particles to be discharged from said shelves through said slots.

6. In an apparatus for separating flats and undersized pieces of coal from an otherwise screened-to-size mass of coal, the combination of an inclined screening element, means for continuously supplying coal and flats from said mass to the upper portion of said screening element, said screening element including a plurality of substantially flat shelves extending transversely thereacross in step-like relation, said shelves

being spaced apart vertically to provide unobstructed openings of sufficient size to permit the passage of undersized pieces of coal and the edge-wise passage of flats therethrough but insufficient to permit the passage of the remainder of said mass of coal, each of said shelves being inclined rearwardly to facilitate movement of said flats and undersized pieces of coal through said openings, and means for abruptly initiating a high speed movement of said screening element forwardly to cause said undersized pieces of coal and flats resting in flatwise relation on said shelves to move by inertia rearwardly through the openings between said shelves, and means for abruptly terminating said high speed forward movement to discharge the remainder of the mass on each shelf onto the shelf below whereby said mass passes progressively down said inclined screening element from shelf to shelf for discharge forwardly therefrom and additional flats and under-sized pieces of coal contained therein may come to rest momentarily on succeeding shelves for discharge rearwardly through said openings.

7. An apparatus for separating flats and under-sized pieces of coal from an otherwise graded-to-size mass of coal comprising an inclined screening element including a plurality of substantially horizontally disposed step members of a width substantially equal to the maximum graded size of the material being treated, 30

said step members being vertically spaced apart to provide open slots therebetween of a predetermined height less than the minimum graded size of the material being treated, and means for imparting to said screening element a recurring motion including an abruptly initiated and abruptly terminated, high speed, horizontal component.

8. An apparatus for separating flats and under-sized pieces of coal from an otherwise graded-to-size mass of coal comprising a screening element including a plurality of step members, each of said step members being of a width sufficient to support only one row of particles of the maximum graded size and being spaced apart vertically from the adjacent step members to provide unobstructed slots therebetween of a height less than the minimum graded size of the material being treated, means for causing a mass of particulated material to pass progressively downwardly over said screening element from step to step whereby discrete particles of said mass come to rest momentarily on said steps, and means for abruptly moving said screening element forwardly at recurring intervals whereby the inertia of said particles causes those having at least one dimension smaller than the minimum graded size to be discharged from said steps through said slots.

EDWARD B. MOORE.
